NECKTIE

Harry L. Frezel, Philadelphia, Pa.

Application December 31, 1936, Serial No. 118,620

4 Claims. (Cl. 2—150)

This invention relates to preformed neckties and has for its object the production of a preformed necktie the pendant portion or portions of which may be adjusted with respect to the knot of 5 after the tie has been mounted on the neck of the wearer.

Preformed neckties having vertically pendant portions now in use are objectionable because of the fact that the pendant portions are seldom attached in the proper axial relationship to the knot portion. As a result either one or both pendant portions will not be in the proper position when worn. It is the object of this invention to produce a preformed necktie which will be 10 free of this objection.

15 I have solved this problem by eliminating the direct attachment of the pendant portions to the knot portion. Instead I attach what I term an adjustment strip to the knot portion and then attach the pendant portions to the free end of 20 the adjustment strip.

25 For the purpose of illustrating my invention, I have set forth in the drawings, which are part hereof, and will now describe two of the many forms into which my novel concept may be incorporated.

30 In said drawings Figure 1 is a rear view of a fragment of my novel tie consisting of the knot portion, the neck portion, and front pendant tie portions as these elements appear at the end of the first step in the manufacture of my novel tie. Portions of certain elements have been broken away for the sake of clearness.

Figure 2 is a section on the line 2—2 of Figure 1.

35 Figure 3 is a view taken similarly to Figure 1 and shows the fragment shown in Figure 1 as it appears at the end of the second step in the making of my novel tie.

Figure 4 is a section taken along the line 4—4 of Figure 3.

40 Figure 5 is a view taken similarly to Figure 1 and shows the fragment aforesaid as it appears when the tie is completed. A portion of the knot cover element has been broken away for the sake of clearness.

45 Figure 6 is a section taken along the line 6—6 of Figure 5.

Figure 7 is a perspective view of a completed tie as the same appears when "made" with the 50 normally inside face on the outside. The lower portion of the front and back pendant members have been broken away for the purpose of permitting the showing of the remaining elements on as large a scale as possible.

55 Figure 8 is a view taken similarly to Figure 1

of a modification and shows the fragment as it appears at the end of the first step in the manufacture of the tie.

Figure 9 is a section taken along the line 9—9 of Figure 8.

Referring more particularly to Figures 1 to 7 of the drawings, wherein similar reference numerals denote similar parts, reference numeral 1 designates my novel tie as a unit which consists of the knot portion 2, the adjustment strip 3 10 attached along one of its edges 4 to the body member 18 of the burlap element 17 of the knot portion 2 by the line of stitches 5, the adjustment strip 6 attached along one of its edges 7 to said burlap element body member 18 by the 15 line of stitches 8, the combined neck and rear pendant portion 9 attached along its edge 10 to the free edge 11 of the adjustment strip 3 by the line of stitches 12, and the front pendant portion 13 attached along its edge 14 to the edge 20 15 of the adjustment strip 6 by the line of stitches 16.

To make my novel tie shown in Figures 1 to 7, I first form the individual elements and then 25 assemble the elements so formed. In the forming of said elements and making said assembly I proceed as follows:

I take a piece of buckram 17, turn its edges as shown at 19, and attach said edges to the body portion 18 by means of the line of stitches 20 30 thus forming the two tubular elements 21. Into each of the tubular elements 21, I insert a leg 24 of the U-shaped wire 22 and I fasten the base 23 of the wire 22 to the body portion 18 of the buckram 17 by means of staples 25.

I form the combined neck and back pendant portion 9 and the front pendant portion 13 in the manner well known in the art. I attach the edge 11 of the adjustment strip 3 to the edge 10 of the combined neck and rear pendant portion by means of the stitches 12 thus forming a unit 40 consisting of the combined neck and rear pendant portion 9 and the adjustment strip 3. I form a unit consisting of the front pendant portion 13 and the adjustment strip 6 by attaching them 45 together near their edges 14 and 15 by means of the line of stitches 16.

I place the knot cover element 26 upon the inner face 27 of the buckram element 17 and attach it thereto by means of paste 28. Then I attach 50 the free end 4 of the adjustment strip 3 to the body member 18 of the buckram element 17 by means of the line of stitches 5 and the free end 7 of the adjustment strip 6 to the body member 18 of the buckram 17 by means of the line of 55

(and the foregoing operations have been completed.)

I now move the knot cover element 26 from the position shown in Figures 1 and 2 to that shown in Figures 3 and 4 and thence to that shown in Figures 5 and 6. Then I connect the free ends 29 of the knot cover piece 26 by means of the line of stitches 30. (Figures 5 and 6 show my novel tie as it appears at the end of the steps set forth in this paragraph.)

Then I complete the tie by bending the knot portion shown in Figure 5 and causing it to assume the shape shown in Figure 7.

15 The structure shown in Figures 8 and 9 differs from that shown in Figures 1 and 2 only in the fact that a single adjustment strip 31 has been substituted for the two adjustment strips 3 and 6.

20 In making the tie disclosed in Figures 8 and 9 I depart only in the following particulars from the method followed in the making of the ties shown in Figures 1 to 7.

Instead of forming a unit consisting of the adjustment strip 3 and neck rear pendant portion 9 25 and another unit consisting of the adjustment strip 6 and front pendant portion 13 and attaching each of these units to the body member 18 of the buckram 17, I form a single unit consisting of the adjustment strip 31 to one end 32 of which I 30 attach the end 19 of the neck and rear pendant portion 9 by means of the stitches 33 and to the other end 34 of which I attach the end 14 of the front pendant portion 13 by means of the line of stitches 35. Then I attach the adjustment strip 31 to the body portion 18 of the buckram 17 by means of the line of stitches 36 thus connecting the unit to the buckram 17.

The above disclosure is to be understood as being by the way of illustration only and not by the 40 way of limitation since many changes may be made in the device here shown without departing from the spirit of my invention which consists in attaching either one or two adjustment strips to the knot portion of a tie and attaching the pendant portion or portions of the tie to said adjustment strip or strips. The use of adjustment strips makes it possible to adjust the pendant portions of the tie to the proper positions with respect to the knot.

50 Having described my invention what I claim as new and useful is:

1. A preformed necktie comprising a knot portion having a longitudinal gap formed in the rear thereof and consisting of a base member of stiff material and a cover member of flexible material; a short flexible strip disposed within and stitched

ends; a front pendant portion upper end only to one of the free ends; a flexible strip; a combined neck and rear pendant portion stitched at its upper end only to the other of the free ends of said flexible strip; said stitching connecting said flexible strip to said knot portion and said pendant portions falling wholly within and being concealed by the knot portion material.

2. A preformed necktie comprising a knot portion having a longitudinal gap formed therein and consisting of a base member of stiff material and a cover member of flexible material; a short flexible strip disposed within said knot portion, stitched to the base member of said knot portion, and terminating in two free ends; a front pendant portion stitched at its upper end only to one of the free ends of said flexible strip; a combined neck and rear pendant portion stitched at its upper end only to the other of the free ends of said flexible strip; said stitching connecting said flexible strip to said knot portion and said pendant portions falling within and being concealed by the flexible material of said knot cover member.

3. A preformed necktie comprising a knot portion having a longitudinal gap formed in the rear thereof and consisting of a base member of stiff material and a cover member of flexible material; two short flexible strips each disposed within said knot portion, each attached near one of its ends to said knot portion and each terminating in an end which is entirely free of said knot portion; a front pendant portion stitched to the free end of one of said flexible strips; a combined neck and rear pendant portion stitched to the free end of the other of said flexible strips; said stitching connecting said flexible strips to said knot portion and pendant portions falling within and being concealed by said knot material.

4. A preformed necktie comprising a knot portion having a gap formed in the rear thereof and consisting of a base member of stiff material and a cover member of flexible material; a combined neck and rear pendant portion attached to said knot portion; a short flexible strip disposed within and stitched to said knot portion and terminating in at least one free end; a front pendant portion stitched at its upper end only to said free end of said flexible strip; said stitching connecting said flexible strip to said knot and pendant portions falling within and being concealed by said knot material.

HARRY L. FREZEL.
